ATTORNEY

UNITED STATES PATENT OFFICE.

LOUIS NORDLINGER, OF NEW YORK, N. Y., ASSIGNOR TO THE NORDLINGER-CHARLTON FIREWORKS COMPANY, OF SAME PLACE.

DESIGN FOR A CHARGE AND STEM FOR FIRE-CRACKERS.

SPECIFICATION forming part of Design No. 30,659, dated May 2, 1899.

Application filed January 28, 1898. Serial No. 668,357. Term of patent 14 years.

To all whom it may concern:

Be it known that I, LOUIS NORDLINGER, a citizen of the United States, residing in the city, county, and State of New York, have invented and produced a new and original Design for a Combined Stem and Charge for Fire-Crackers and the Like, of which the following is a specification.

My design consists, essentially, of the charge and stem of a fire-cracker comprising a relatively larger cylindrical body portion constituting the charge, said larger portion having suddenly contracted and rounded ends merging into attenuated extensions constituting the stem portion, the exterior of the said body throughout having a spiral effect due to the winding of the covering strip, as shown in the accompanying drawing.

In the accompanying drawing, which shows a side elevation illustrating my design, 1 indicates the charge portion, which is of substantially cylindrical form, with suddenly-contracted rounded ends 2, merging into the stem portions 4, the meeting edges of the spirally-wound covering strip being indicated at 3.

What I claim is—

The design for the charge and stem of a fire-cracker, as herein shown and described.

Signed in the city, county, and State of New York this 26th day of January, 1898.

LOUIS NORDLINGER.
